(57) **CLAIM**

We claim the ornamental design for a refrigerator, as shown and described.

DESCRIPTION

FIG. 1 is a front perspective view of a refrigerator showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is an enlarged view of the encircled portion of FIG. 1;

FIG. 9 is an enlarged view of the encircled portion of FIG. 2; and,

FIG. 10 is a front perspective view of the refrigerator shown in a state of use.

The broken lines in the figures illustrating portions of the refrigerator and environmental structure form no part of the claimed design.

(Continued)

The dot-dash broken lines encircling portions of the claimed design that are illustrated in enlargements form no part of the claimed design.
